UNITED STATES PATENT OFFICE.

ARTHUR A. CHARBONDAUX, OF SPOKANE, WASHINGTON.

DRAG SCRAPER AND EXCAVATOR.

1,258,090.

Specification of Letters Patent.

Patented Mar. 5, 1918.

Application filed December 18, 1916. Serial No. 137,599.

To all whom it may concern:

Be it known that I, ARTHUR A. CHARBONDAUX, a citizen of the United States, residing at Spokane, in the county of Spokane 5 and State of Washington, have invented certain new and useful Improvements in Drag Scrapers and Excavators, of which the following is a specification.

My invention relates to improvements in 10 drag scrapers and excavators.

Scrapers of this type are usually provided with a back-haul line for returning the scoop to its initial position on the supporting cable. One of the principal objects of the 15 present invention is the elimination of this back-haul line as, by so doing, the apparatus may be controlled with greater facility and convenience and by a single operator.

A further object resides in the provision 20 of a novel device of the foregoing character of extremely simple and comparatively inexpensive construction which will accomplish the work for which it is adapted in an efficient and expeditious manner.

Generally speaking, my invention comprises an inclined scraper supporting cable, 25 a scraper carriage haul line, a scraper adjusting line, and winding drums for the control of the cable and lines.

The various elements of the complete organization will be hereinafter more fully pointed out and described in detail in connection with the accompanying drawings, in 30 which—

Figure 1 is a side elevation of the entire apparatus set up for operation and showing the relative arrangement of the parts.

Fig. 2 is a side elevation of the power structure on an enlarged scale, illustrating 40 in detail the cable, lines and tackle thereon.

Fig. 3 is a greatly enlarged view in side elevation showing the scraper carriage, scraper, cable and lines, and

Fig. 4 is a rear end view of the carriage 45 and scraper.

Referring more specifically to the drawings in which like reference characters are used to indicate like parts in the several views, the numeral 1 designates a tower-like 50 supporting structure. A carriage supporting cable 2 which is adapted to be suspended above the area to be excavated, has one end secured to the base of the tower at 3 said cable extending upward and passing over the counter pulleys 4 and 5. A block and

tackle 6 and a power winding drum 7 are adapted to coöperate with said cable 2 to slacken or tighten the latter at the will of the operator. The opposite end of the cable is anchored at 8 in any suitable manner but 60 in a plane below that of the pulleys 4 and 5 in order to provide the required incline of the cable.

The scraper carriage 9 is of rectangular form and consists of two similar frame body 65 members 10 and 11, said carriage being supported upon the cable 2 by the grooved wheels 12 which are disposed between said members and mounted thereon. A scraper or scoop 13 is pivotally mounted at 14 on 70 the pair of depending arms 15 which are adjustably secured for vertical adjustment to the carriage frame members by means of the slots 16 and bolts 17.

The scraper is provided with a bail 18 to 75 which is attached one end of the scraper adjusting line 19 which passes over a pulley 20 mounted on the carriage frame. Said line extends slantwise up over the grooved wheel 21 mounted at the top of the tower 80, 1, its opposite end being secured to a winding drum 22.

A haul line 23 is attached to the carriage at 24 and this line also extends upwardly at an angle over the grooved wheel 25 and 85 on to winding drum 26. Power for operating the several drums is transmitted in the usual manner from an engine 27 or other power plant.

The successive scooping and dumping 90 operations are accomplished substantially as follows: The operator first disposes the scraper carriage at the desired point along the supporting cable 2 by hauling in or paying out the haul line 23, in the latter case 95 the slant of the cable causing the carriage to gravitate to such point, no back-haul line being required. When necessary the scraper may be tilted to the desired angle or pitch upon its pivot by slackening the adjusting line 19 to bring the scraper into proper contact to enter the ground. This operation is necessary when it is desired to scoop up a considerable "bite" at a given place. In the same operation the cable 2 100 is paid out so as to lower the scoop and its carriage bodily so that the scoop or scraper edge will sufficiently engage the earth. Then, when the bucket is filled by drawing in on the line 23 the adjusting line 19 is 110

shortened so as to raise the scraper edge and then the receptacle is raised bodily and perpendicularly by taking up the cable 2.

Ordinarily, however, the scraper is simply, 5 lowered to engage the ground by slackening cable 2 and the carriage drawn forward. The dumping is, of course, accomplished by paying out the scraper adjusting line 19 when the receptacle reaches the proper 10 point. Return travel of the carriage is expedited upon increasing the degree of slant of the supporting cable by shortening the same.

While I have described and illustrated 15 only one embodiment of my invention, it is to be understood that I do not limit myself to the specific construction set forth but, on the other hand hereby expressly reserve the patent right to make various changes 20 therein, as long as in so doing, I do not de-

part from the spirit and scope of the invention as defined in the appended claim.

Having described and explained my invention, its construction, operation, and advantages, I claim as new and desire to secure by Letters Patent of the United States:

The combination in an excavating apparatus including a supporting cable, of a carriage thereon comprising a pair of spaced frame members and a pair of rear, slotted, 30 arms adjustably secured thereto, a scraper located below the carriage and hinged at the lower ends of these arms, a guide pulley at the front of the carriage and an adjusting line passed over said pulley and attached 35 to the scraper, and a single haul line attached to the frame.

In testimony whereof I affix my signature.

ARTHUR A. CHARBONDAUX.
